UNITED STATES PATENT OFFICE.

WILLIAM HENRY SUMBLING, OF TORONTO, ONTARIO, CANADA.

SAFETY RELEASE FOR POWER-DRIVEN ROLLS OR CUTTERS.

Application filed June 15, 1921. Serial No. 477,850.

To all whom it may concern:

Be it known that I, WILLIAM HENRY SUMBLING, a subject of the King of Great Britain, of the city of Toronto, county of York, Province of Ontario, Canada, have invented certain new and useful Improvements in Safety Releases for Power-Driven Rolls or Cutters, of which the following is a specification.

10 My invention relates to a safety release for power-driven rolls or cutters, and the object of the invention is to provide means under the control of the operator of the machine to positively and quickly render 15 inoperative the means holding a pair of rolls, or cutters, in co-operative relationship so that in case the hand or hands of the operator be caught therebetween, the same may be sufficiently separated while still 20 rotating to permit the hand or hands to be withdrawn before any serious damage can be done, and in the following specification I shall describe a disclosure within my invention relating particularly to wringing machines, and what I claim as new will be set 25 forth in the claim forming part of this specification.

Fig. 1 is a side elevation of a wringing machine showing the same constructed to 30 embody the principle of my invention. Fig. 2 is an end elevation of the principal parts shown in Fig. 1, and Fig. 3 is a horizontal cross-section on the line 3—3, Fig. 2.

In the drawings, like characters of reference refer to the same parts.

As before set forth, the principle of my invention is disclosed in connection with power-driven wringing machines, though the principle thereof may be utilized in various types of machines where a pair of substantially parallel rolls, or cutters, operate on the work to change the form or state thereof.

In the exemplary disclosure within my invention the rolls are yieldingly held so that they may automatically adjust themselves to the thickness of the article passing therebetween, but such automatic adjustment is not essential to the broad application of the principle of my invention. But it is of the essence of the invention that the primary pressure-exerting means which hold the rolls or cutters in co-operative relationship shall be made inoperative when necessary, and that when out of operation the weight thereof shall not interfere with the separation of

the rolls or cutters: In other words, the primary pressure-exerting means when in operation positively dominates or controls the relationship of said rolls or members, and when out of operation said means do not interfere, by exerting any weight or pressure against the rolls or members, with the separation thereof.

Where the rotary members are geared together, the range of separating movement may be as desired, that is to say, the separation thereof may be sufficient to throw them out of gear.

Are a pair of standards, preferably 70 tubular in form for the major portion of their length, and mounted in each of the said standards is a pair of boxes B in which are journaled the shafts C of the rolls D. These shafts are provided with suitable gear 75 wheels E and F in order that they may co-operated, as is common in the art.

Resting upon the upper box B in each standard A is a coiled spring G and resting upon the top of each of these springs is a 80 presser-bar H. Positioned within each of the standards A is a box I in which have bearing the trunnions J of the safety-release device, which comprises levers K coupled together at their outer ends as by 85 means of a bar L. Co-operating with the top of each of the standards A is a screw 2 which is preferably threaded through the cap 3. Each of these screws has a hand wheel 4, and the lower end of each of the 90 said screws is suitably coupled to its associated box I.

Of course the screws 2 are used to regulate the ultimate pressure to be exerted against the springs G, and upon referring 95 particularly to Figs. 1 and 2 it will be observed that since the levers K are in contact with the presser-bar H, the springs G are held under compression and consequently the rolls D are tightly held together. 100 In the disclosure made of my invention, the safety-release device may be shoved away from the operator, or pulled towards him, and when moved sufficiently in either direction around the trunnions J, the pressure 105 against the bar H will be immediately released with the result that the rolls D may be separated to permit the withdrawal of the hand.

When the safety-release device is in dotted position shown in Fig. 2, it will be observed that by reason of the slot 5 formed

in the standards A, abundance of room is provided for the expansion of the springs G.

When it is desired to hold the rolls D again under pressure, when my form of

5 safety-release device disclosed is used, the screws 2 must be retracted sufficiently so as to raise the boxes I far enough to permit the ends 6 of the levers K to be positioned as shown in Figs. 1 and 2 in contact with the 10 bar H. The screws 2 are then operated, and as the boxes I are lowered the levers K move the presser-bar H to compress the springs G.

Upon referring particularly to Figs. 1 and 2 it will be observed that since there is 15 a clear space beneath the boxes I, when the safety-release device is moved out of contact with the bar H, the said device as well as the boxes I, will be supported by the screws 2, and consequently none of the weight of 20 these parts will be carried by the bar H at this time.

My preferred manner of associating the screws 2 each with its box I, is to form in the upper side of each of the said boxes a 25 T-shaped slot 7 thus providing flanges 8 with which engages the head 9 of each screw 2 when the safety-release device occupies the dotted position shown in Fig. 2. It will be observed that one end of the slot 7 is 30 open so as to permit of the ready assembling of the boxes I and screws 2.

The standards A may be coupled together at each side by any suitable means such as nut-provided tie-rods 10 which are held in 35 the lugs 11 forming part of said standards. 12 is a nut-provided tie-rod to couple the lower ends of the standards A together in any well-known manner. This tie-rod may be used to mount the apron 13 thereon.

40 The ends of the presser bar H, preferably project beyond the standards A, and are provided with suitable means to prevent any considerable longitudinal displacement of

said bar; such means may be in the form of pins 14 carried by said bar and which come 45 into contact with the standards A and form stops.

While I have described what I consider to be the best embodiment within my invention it must be understood that the principle 50 may be embodied in other different forms, and I desire not to be limited beyond the requirements of the prior art and the terms of my claim.

In this disclosure of my invention, it will 55 be observed that since the bar L is directly above the rolls D, in case the operator's both hands be caught, it is possible for him to reach forward with the head and release the safety-release device. 60

In the exemplary disclosure of my invention, the screws 2 and supports therefor; the boxes I, trunnions J, levers K, and bar L form what I call the primary pressure-exerting elements, while the presser-bar H, 65 springs G, and the upper pair of boxes B form what I call the secondary pressure-exerting elements.

What I claim is:

In combination a frame including end 70 standards; a pair of rolls mounted to have bearing in said standards; a coiled-spring mounted in each of said standards to rest in contact with the upper of said rolls; a presser-bar resting upon said springs and 75 adapted to be held in co-operative relationship to said standards; a box located within each of said standards near the top thereof; a screw associated with each of the said boxes and having threaded connection with 80 the top of each of said standards, and pressure-exerting means journaled at each end in said boxes and normally in disengagable contact with said presser-bar, the whole designed to co-act for the purpose set forth.

WILLIAM HENRY SUMBLING.
